UNITED STATES PATENT OFFICE.

JACOB WAX, OF BROOKLYN, NEW YORK.

DESIGN FOR A FINGER RING.

Application filed February, 21, 1925. Serial No. 12,452. Term of patent 3½ years.

To all whom it may concern:

Be it known that JACOB WAX, a citizen of the United States, and resident of the city of New York, borough of Brooklyn, in the county of Kings and State of New York, has invented a new, original, and ornamental Design for Finger Rings, of which the following is a specification, reference being had to the accompanying drawing, forming part thereof, in which—

Fig. 1 is a side elevational view of a finger ring embodying my new design;

Fig. 2 is an edge elevational view thereof; and

Fig. 3 is a top plan view thereof.

I claim:

The ornamental design for a finger ring as shown.

Dated New York city, February 20th, 1925.

JACOB WAX.
